ROTARY COMBUSTION ENGINE APEX SEAL LUBRICATION

This invention relates to rotary engine apex seal lubrication and more particularly to direct apex seal lubrication through a metering device that is closed by a spring valve in response to combustion pressure.

It is present commercial practice in rotary combustion engines to provide an oil metering pump that is driven by the engine and controlled with the engine throttle to meter oil for gas seal lubrication at a rate that increases with increasing engine load. The oil thus metered is then mixed with the fuel for delivery to the chamber walls on which the seals slide. In an effort to provide a more efficient seal lubrication arrangement, there has been proposed direct apex seal lubrication using oil from inside the rotor as in U.S. Pat. No. 3,261,334 and copending U.S. application Ser. No. 400,365 now U.S. Pat. No. 3,884,601 which is assigned to the assignee of the present invention. And now it has been found that with the present commercial method of apex seal lubrication which coats the entire walls of the chambers, this oil coating can absorb excessive hydrocarbons during combustion and later release them during exhaust. Thus, there is added impetus for an efficient, readily manufacturable and durable arrangement that will provide direct lubrication of the apex seals using oil from the interior of the rotor but without allowing the combustion pressure to back-pressure this oil supply.

In the present invention there is provided in the bottom of each apex seal slot in the rotor one or more porous plugs of predetermined porosity which meter oil from the interior of the rotor directly to the apex seals. In addition, a simple reed valve between the normal apex seal spring and the bottom of the apex seal slot responds to combustion pressure to close each plug to prevent this pressure from back-pressuring the oil in the rotor. Thus, the desired oil metering at very low rates is provided by inserts which can be more readily manufactured yet are more durable as compared, for example, with a drilled orifice. Furthermore, the reed valve is independent of the apex seal spring so that its responsiveness to accomplish the desired effect can be closely predicted and controlled without affecting the apex seal spring.

An object of the present invention is to provide a new and improved rotary combustion engine apex seal lubrication arrangement.

Another object is to provide a seal lubrication arrangement on the rotor in a rotary combustion engine that meters oil directly to spring biased apex seals on the rotor through porous plugs which are closed by spring valves in response to combustion pressure.

These and other objects of the present invention will become more apparent from the following description and drawing in which:

FIG. 1 is a view with parts in section and some parts shown schematically of a rotary combustion engine having apex seal lubrication arrangements according to the present invention.

FIG. 2 is a view taken along the line 2-2 in FIG. 1.

FIG. 3 is an enlarged view taken from FIG. 1 of one of the apex seal lubrication arrangements.

The seal lubrication provided according to the present invention is particularly suited for use in a rotary combustion engine of the planetary type such as shown in FIGS. 1 and 2. The engine comprises a metal housing

10 which in a single rotor arrangement has basically three parts, namely a rotor housing 12 having an inwardly facing inner peripheral wall 14 and a pair of end housings 16 and 18 having parallel, oppositely facing, spaced inner end walls 20 and 22, respectively. The housing parts are secured together by bolts, not shown, and the inner housing walls 14, 20 and 22 cooperatively provide a cavity 24. As shown in FIG. 2, the peripheral wall is in the shape of a two-lobed epitrochoid or a 10 curve parallel thereto whose center line is indicated at 26. A crankshaft 28 extends through the cavity 24 and is rotatably supported in sleeve bearings 30 and 32 which are secured in collars 34 and 36 that are bolted to the end housings 16 and 18 as shown in FIG. 1, the 15 crankshaft axis being coincident with the center line 26, parallel to the peripheral wall 14 and at right angles to the end walls 20 and 22. The crankshaft 28 is provided in the cavity 24 with an eccentric 38. A hollow metal rotor 40 has a hub 41 having a sleeve bearing 42 secured therein which is received on the eccentric 38 so that the rotor is thereby supported for rotation about the eccentric's center line 44 which is thus the rotor's 20 axis.

The rotor 40 has the general shape of a triangle with 25 two parallel side walls 46 and 48 at right angles to the rotor axis which face and run close to the end walls 20 and 22, respectively, and a peripheral wall 50 having three arcuate outer faces which face the peripheral wall 14 and cooperate therewith and with the end walls 20 30 and 22 to define three variable volume working chambers 52. Sealing of these three chambers from each other is effected by sealing means comprising three apex seals 54 each of which is mounted in an axially extending slot 55 at each apex or corner of the rotor 40 35 that extends the width thereof. Three arcuate side seals 56 are mounted in accommodating grooves in each rotor side and extend adjacent the rotor faces between two of the apex seals 54. Three cylindrical corner seals 58 are mounted in cylindrical blind bores 59 in each 40 rotor side at the rotor corners with each corner seal providing sealing between the ends of two side seals and one apex seal as shown in FIG. 2. The apex seals 54 are biased by springs 60 to continuously engage the peripheral wall 14 while the side seals 56 and the corner seals 58 are biased by springs 61 and 62, respectively, to continuously engage the respective end walls 20 and 22 with the complete gas seal arrangement acting 45 to seal the working chambers.

With the two-lobed peripheral wall 14 and the three 50 corner rotor 40, each of the working chambers 52 sequentially expands and contracts between minimum and maximum volume twice during each revolution in fixed relation to the housing by forcing the rotor to rotate at one-third the speed of the crankshaft. This is accomplished by gearing comprising an internal tooth rotary phasing gear 63 which is fixed in side 48 of the rotor concentric with the rotor axis. The gear 63 55 meshes with an external tooth annular stationary phasing gear 64 which is freely received about and is concentric with the crankshaft 28 and is made stationary by being formed integral with the left-hand end of the right-hand collar 36 as shown in FIG. 1. The gear 63 has one and one-half times the number of teeth as the gear 64 to provide the required speed ratio of 3:1 between the crankshaft and the rotor.

A combustible air-fuel mixture from a suitable carburetor arrangement, not shown, is made available to

each working chamber 52 by an intake passage 66 shown in FIG. 2. Passage 66 extends through the engine housing and opens to the cavity through aligned ports 67 in the end walls 20 and 22 that are located on the leading side of cusp 68 of the peripheral wall 14 relative to the direction of rotor rotation indicated by the arrow in FIG. 2, there being only one such intake port appearing in this view. A single channel or recess 69 is provided in the center of each chamber face of the rotor to provide for the transfer of the working gas part the peripheral wall's other cusp 70 while the rotor face is at or near a top-dead-center position, as shown in FIG. 2, so that the chambers are not divided by the cusp 70 at the time when combustion is occurring therein. A spark plug 72 is mounted in the rotor housing 12 adjacent the cusp 70 with its electrodes exposed to the passing working chambers. As the rotor plane-tates, the working chambers successively draw in fuel mixture as the rotor sides radially outward of the side seals 56 periodically uncover the intake ports 67. The fuel mixture is then trapped in each working chamber and compressed and when the rotor face of this chamber is in the vicinity of top-dead-center, this mixture is ignited at the completion of the compression phase, there being provided a suitable ignition system, not shown, for applying voltage to the spark plug at the proper time. Upon ignition of the mixture in each working chamber, the peripheral wall 14 takes the reaction forcing the rotor to continue rotating while the gas is expanding. The leading apex seal 54 of each of the working chambers eventually traverses an exhaust passage 74 in the rotor housing on the trailing side of the cusp 68 whereby the exhaust products are then expelled to complete the cycle.

Describing now the lubrication of this arrangement, except for the seals, and also the cooling of the rotor, oil from the engine drains to a sump 75 from which it is drawn by a suitable pump 76 powered from the engine crankshaft 28 and then delivered via a delivery line 78 to an axial oil passage 80 through the crankshaft 28. Radial oil passages 82, 84 and 86 in the crankshaft deliver oil from the passage 80 to lubricate the sleeve bearings 30, 42 and 32, respectively. The hollow rotor 40 is of the so-called I-beam type as shown in cross-section with a central radially extending rib 89 between the rotor's peripheral wall 50 and the hub 41 and with the rotor side walls 46 and 48 extending radially inward from the peripheral wall with annular spaces left between these side walls and rotor hub. A radial oil passage 94 in the crankshaft 28 delivers oil from the passage 80 radially outward between the right-hand side of the eccentric 38 and the left-hand side of the timing gears 63 and 64 to the interior of the rotor for cooling. The oil passes from the right to the left side of the central rib 89 via axially extending, angularly spaced holes 96 therethrough with the oil carrying the heat from the rotor by passing out the opposite side openings in the rotor to annular cavities 98 and 99 in the respective end walls 20 and 22. The cavities 98 and 99 are connected to branches of a return line 100 that drains to sump 75. A circular oil seal 102 mounted in an accommodating groove in each side wall of the rotor so that it is centered on the rotor axis in a radial location inward of the side seals 56 engages the opposite housing end wall to prevent the oil from reaching the gas seals.

The engine structure thus far described is of a conventional presently commercial type with lubrication of

all but the gas seals normally provided by the pump 76 feeding oil to the sleeve bearings and the rotor cooled by the oil circulated therethrough. In such an engine, proper lubrication of the apex seals 54 is very important and is normally provided by an oil metering pump that meters oil to either mix with the fuel prior to its induction into the working chambers or feed through oil feed ports in the housing directly into the chambers with this metering controlled to increase with increasing engine load to assure adequate seal lubrication with varying engine conditions. Others have taught that more efficient seal lubrication may be obtained by delivery of oil from within the rotor directly to the apex seals however their proposed means for effecting such delivery are generally either not well suited to mass production, are not very durable or impose substantial modifications or material changes for the rotor. These objections are overcome by the present invention which as best shown in FIG. 3 has apex seal lubricant metering means at each apex of the rotor comprising a pair of counterbored holes 104 which are located on opposite sides of the rib 89 and extend radially through the rotor's circumferentially extending wall 50 between the interior of the rotor and the bottom of the associated apex seal slot 55. A porous plug 106 is mounted in each of the holes 104 and has a predetermined porosity such that the centrifugal forces on the body of cooling oil in the rotor are effective to force oil to diffuse out through the plugs 106 and thus into the apex seal slot 55 from where the oil eventually migrates to the wear surface of the apex seal 54 and also to the corner seals 58 and from there to the side seals 56, this porosity being determined to provide a metered rate of oil for such lubrication that will adequately and efficiently lubricate the seals at minimum speed and load. Then as the engine speed increases, the metered oil delivered by the porous plugs 106 increases at an exponential rate with increasing rotor speed as the result of the centrifugal force to assure good, but not excessive, gas seal lubrication over the engine's entire speed range.

In the preferred embodiment, the porous plugs 106 are formed of a powdered metal with their predetermined porosity accomplished by the material mix and the manufacturing process, the required porosity thus being provided in a manner readily suited to high-volume mass production. A typical type of material mix giving lubricant diffusion porosity suitable for use in the rotary combustion engine environment comprises predominantly iron with some graphite and lubricant. The powder is briquetted in the plug shape to a certain green density and then a small percentage of copper is infiltrated into the briquetted powdered metal plug during sintering thereof, this percentage of copper being dependent on the green part weight and decreasing with increasing density. During sintering, the copper infiltrates the then relatively highly porous plug structure to fill a high percentage of the interstices yet leave enough interconnected voids to produce the desired diffusion rate.

To prevent the combustion pressure that reaches the bottom of the apex seal slot 55 from back-pressuring the oil within the rotor, there is provided a reed valve 108 made from a flat piece of spring steel that is arranged between the apex seal spring 60 and the bottom of the apex seal slot 55, the reed valve 108 thus actually serving as the seat for the apex seal spring 60 but in no way affecting the operation thereof nor permitting the

apex seal spring to effect its operation. The reed valve 108 has a tang 110 lanced from its middle which projects downwardly into a locator hole 112 in the bottom of the apex seal slot 55 to center the reed valve with its oppositely extending flexible portions always arranged over the porous oil metering plugs 106. The spring rate of the reed valve 108 is determined to be sufficiently low to permit the aforementioned minimum metered oil supply at engine idle by the flexible portions deflecting in response to the centrifugally generated pressure on the oil through the porous plugs at this rotor speed and whenever the pressure on the reed valve from the combustion chambers exceeds a predetermined amount which is less than the centrifugal fluid pressure developed because of the spring force opposition to the latter, the reed valve 108 closes on the porous plugs. Thus, the combustion pressure is prevented from affecting the internal oil pressure in the rotor during the time each apex seal slot is exposed to combustion pressure which is once during every rotor revolution.

To illustrate some of the results that have been obtained from actual tests using the structure described, an engine was run for a prescribed time under similar conditions first with a conventional oil metering system having a pump metering oil to the fuel and then with the lubrication system according to the present invention. In these comparative tests, it was found that with the conventional oil lubrication metering system, 190 grams of oil were consumed whereas the oil consumption with the direct oiling arrangement according to the present invention was only 50 grams or only about one-fourth the normal amount of oil consumption. Furthermore, comparative tests also showed both a substantial improvement in fuel economy and a substantial reduction in hydrocarbons.

The above described embodiment is illustrative of the invention which may be modified within the scope of the appended claims.

I claim:

1. A rotary combustion engine comprising an engine housing having an internal peripheral wall and oppositely facing end walls cooperatively defining a cavity, a shaft extending through said cavity and end walls and rotatably supported by said housing, a hollow rotor located in said cavity and rotatably mounted on said shaft and having apexes that remain close to said internal peripheral wall as said shaft and rotor rotate, said rotor having a circumferentially extending wall cooperating with said peripheral wall of said housing an oppositely facing radially extending side walls cooperating with said end walls of said housing to provide a plurality of chambers between said apexes that are spaced about and move with said rotor while varying in volume as said rotor and said shaft rotate, apex seals mounted in slots in said rotor at said apexes for engaging said peripheral wall, a spring arranged between the bottom of each said slot and the bottom of the associated apex seal for urging the apex seal outwardly against said peripheral wall, a source of oil, passage means for delivering the oil to and from the interior of said rotor, said rotor having a central rib therein extending radially inwardly from said circumferentially extending wall, and apex seal lubricant metering means mounted in said rotor at each said apex for metering oil from the interior of said rotor to the associated apex seal slot without permitting combustion pressure to backpressure

the oil in said rotor whereby oil is effectively delivered directly to the wear surfaces of the apex seals, each said apex seal lubricant metering means comprising a pair of porous plugs mounted in lubricant delivery holes in said circumferentially extending wall connecting the interior of said rotor on opposite sides of said rib to the bottom of the associated apex seal slot, said porous plugs having a porosity effective to permit oil to diffuse therethrough as a result of centrifugal forces on the body of oil within said rotor and at a rate sufficient to adequately lubricate said apex seals at minimum rotor speed and load and as a result of continuing centrifugal action on the oil in the interior of said rotor providing increasing oil delivery to increase the lubrication of said apex seals with increasing rotor speed, a flat spring valve arranged between each said apex seal spring and the bottom of the associated apex seal slot and extending at opposite ends along flexible portions over the associated porous plugs for opening the porous plugs only when the oil pressure acting on the porous plug side of the flexible portions exceeds the gas pressure from said chambers acting on the opposite side by a predetermined amount.

2. A rotary combustion engine comprising an engine housing having an internal peripheral wall and oppositely facing end walls cooperatively defining a cavity, a shaft extending through said cavity and end walls and rotatably supported by said housing, a hollow rotor located in said cavity and rotatably mounted on said shaft and having apexes that remain close to said internal peripheral wall as said shaft and rotor rotate, said rotor having a circumferentially extending wall cooperating with said peripheral wall of said housing and oppositely facing radially extending side walls cooperating with said end walls of said housing to provide a plurality of chambers between said apexes that are spaced about and move with said rotor while varying in volume as said rotor and said shaft rotate, apex seals mounted in slots in said rotor at said apexes for engaging said peripheral wall, a spring arranged between the bottom of each said slot and the bottom of the associated apex seal for urging the apex seal outwardly against said peripheral wall, a source of oil, passage means for delivering the oil to and from the interior of said rotor, said rotor having a central rib therein extending radially inwardly from said circumferentially extending wall, and apex seal lubricant metering means mounted in said rotor at each said apex for metering oil from the interior of said rotor to the associated apex seal slot without permitting combustion pressure to backpressure the oil in said rotor whereby oil is effectively delivered directly to the wear surfaces of the apex seals, each said apex seal lubricant metering means comprising a pair of porous plugs mounted in lubricant delivery holes in said circumferentially extending wall connecting the interior of said rotor on opposite sides of said rib to the bottom of the associated apex seal slot, said porous plugs having a porosity effective to permit oil to diffuse therethrough as a result of centrifugal forces on the body of oil within said rotor and at a rate sufficient to adequately lubricate said apex seals at minimum rotor speed and load and as a result of continuing centrifugal action on the oil in the interior of said rotor providing increasing oil delivery to increase the lubrication of said apex seals with increasing rotor speed, a flat spring valve arranged between each said apex seal spring and the bottom of the associated apex seal slot and extend-

ing at opposite ends along flexible portions over the associated porous plugs for opening the porous plugs only when the oil pressure acting on the porous plug side of the flexible portions exceeds the gas pressure from said chambers acting on the opposite side by a predetermined amount said flat spring valve also having a cen-

ter projection projecting radially inwardly into a locator hole in the bottom of the associated apex seal slot to maintain the flat spring valve in proper valve relationship with the associated porous plugs.
